Attorney

UNITED STATES PATENT OFFICE

HAROLD A. HORNER, OF WILKINSBURG, PENNSYLVANIA

SMOKE INDICATOR

Application filed March 16, 1931. Serial No. 523,009.

My invention relates to a smoke indicator adapted for connection with a flue bridge establishing communication between the combustion chamber and the smoke stack, of any type of combustion apparatus.

The primary object of the invention is to provide a smoke indicator of the character described, which will function automatically to indicate to an observer, stationed at the combustion apparatus, the density of the by-products of combustion passing from the combustion chamber to the associated smoke stack, so that the operator, with such knowledge, is intelligently enabled to properly regulate or control the furnace apparatus for maximum efficiency on a minimum fuel consumption.

Other objects of the invention are to provide a device of the class stated, which may be readily mounted in position on a flue bridge already erected, which requires no changes to associated structures and no additional materials or parts except that embodied in the invention itself, which is simple in its construction and arrangement, durable and efficient in its use, attractive in appearance, compact, positive in its action, and comparatively inexpensive to manufacture, install, operate and maintain.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawing wherein like numerals of reference designate corresponding parts throughout the several views:

Figure 1 is a front elevational view of a smoke indicator constructed in accordance with the invention.

Figure 2 is a sectional view on line 2—2, Figure 3, which latter is a top plan view of the device.

Referring in detail to the drawing, 1 de-

notes a cylindrical flue bridge, which may be constructed to conform to any type of flue bridge commonly employed for establishing communication between the combustion chamber of a combustion apparatus and its associated smoke stack.

My improved smoke indicator comprises a light casing 2 providing a reflector chamber 3, and a vision casing 4 providing a reflector chamber 5. The light casing 2 is formed with a reduced inner end 6, which is permanently and rigidly fixed to one side of the flue bridge 1 in any suitable manner. The inner end 6, of the light casing 2, is open thereby establishing communication between the reflector chamber 3 and the flue bridge 1.

The vision casing 4 is carried in position by a cylindrical supporting tube 7, having an enlarged inner end 8, which is permanently and rigidly fixed to the flue bridge 1, in any suitable manner, at a point diametrically opposed to the reduced open end 6 of the light casing 2. The supporting tube 7 is open at both of its ends, and establishes communication between the flue bridge 1 and the reflector chamber 5 of the vision casing 4.

The light casing 2 with its reduced inner end 6, and the vision casing 4 with its supporting tube 7, are all longitudinally aligned relatively to each other and extend horizontally on respective sides of the flue bridge 1.

The light casing 2 is provided with a light tube 9, which extends vertically upward from the top of the former. The lower end of the light tube 9 is open to communicate with the reflector chamber 3.

An electric lamp 10 is positioned in the light tube 9 and carried in a socket 11, which is fixed in a supporting plate 12. The latter is removably mounted against the outer wall of the light tube 9 by suitable attaching elements 13. The outer wall of the light tube 9 is formed with an aperture 14 for the passage of the lamp 10 therethrough into the light tube 9.

The upper end of the light tube 9 is open and provided with a flanged cover 15. A portion of the latter depends into the open upper end of the light tube 9 in close proximity above the lamp 10 and has a polished inner

face to provide a lamp reflector 16 for directing the light from the lamp 10 downwardly through the light tube 9 and into the reflector chamber 2.

3 A mirror reflector 17 is removably mounted in the chamber 3 and disposed outwardly at its upper end at an angle of approximately forty-five degrees. The mirror reflector 17 is maintained in position directly beneath the open lower end of the light tube 9, by suitable guide members 18, which are fixed to respective side walls of the light casing 2. The mirror reflector 17 is inserted into the light casing 2 through a slot 19 formed in the top of the latter, and extends transversely throughout the width of the chamber 3.

20 A vertically extending transparent lens 20 is mounted in the chamber 3, inwardly 20 of the light tube 9 and of the reflector mirror 17. The transparent lens 20 is maintained in position by guide members 21, which are fixed to respective side walls of the light casing 2. The transparent lens 20 is inserted 25 into the light casing 2 through a slot 22 formed in the top of the latter and also extends transversely throughout the width of the chamber 3.

30 The front side wall of the light casing 2 is formed with an opening 23, which is provided with a removable cap 24. The removal of the latter facilitates the frequently required cleaning of the transparent lens 20 through the opening 23, without necessitating the removal of said lens 20 from the light casing 2. The transparent lens 20, while 35 preferably sealed in position to prevent the passage of any extraneous matter past same, is removable to permit its replacement when required.

40 Another mirror reflector 25 is removably mounted in the chamber 5, of the vision casing 4. The mirror reflector 25 is disposed inwardly at its upper end at an angle of approximately sixty degrees, and extends transversely throughout the entire width of the chamber 5. The mirror reflector 25 is inserted 45 into the chamber 5 through a slot 26 formed in the top of the vision casing 4, and maintained in position by guide members 27, which are fixed to respective side walls of the vision casing 4.

50 A vision tube 28 having open upper and lower ends, depends vertically from the bottom of the vision casing 4, directly beneath the angularly disposed mirror reflector 25. A translucent viewing lens 29, preferably constructed from frosted glass, is mounted horizontally in the vision tube 28 and extends over the entire transverse area of the latter. The translucent lens 29 is inserted into the vision tube 28 through a slot 30 formed in the front wall of the latter, and is supported 55 in position on a pair of guide members 31,

which are fixed to respective end walls of said vision tube 28.

60 The translucent lens 29, while removable when required, is preferably sealed in position to render same impervious to the passage of light and of any extraneous matter past same. The supporting tube 7 includes a shiftable outer portion 32, of well known construction, to allow the sideway adjustment of the vision tube 28 when focusing the 75 latter to accommodate the view of the observer. Such adjustment does not disturb the longitudinal alignment of light and vision chambers 3 and 5.

70 It will be noted that the light chamber 2, vision chamber 4, and vision tube 28 are preferably rectangular in transverse cross section to more readily adapt same to the correspondingly shaped mirror reflectors and lenses in the manner stated. It is evident, 85 however, that the configuration of these parts may be varied to best meet conditions, without departing from the spirit of the invention.

80 The slots 20 and 22 in the light casing 2, and the slots 26 and 30 in the vision casing 4, are preferably covered, in any suitable manner to render same impervious to the passage of the light therethrough, as such passage of light would tend to diminish the efficiency of the device.

90 In practice, the operation of my improved smoke indicator is as follows:—The lamp 10 is illuminated, and the light rays therefrom will be directed against the mirror reflector 17 in the chamber 3 by the reflector 16. The light rays will be reflected from the mirror reflector 17 in the chamber 3 to the mirror reflector 25 in the chamber 5. The light rays, 100 in being reflected from the mirror reflector 17 to the mirror reflector 25, are intensified by passing through the transparent lens 20 and further accentuated in passing through the reduced casing end 6. The light rays 105 penetrate the smoke passing through the flue bridge 1 and are amplified on entering the enlarged end 8 of the supporting tube 7 passing through the latter into the chamber 5 and against the mirror reflector 25.

110 The observer gazes upwardly into the vision tube 28 at the translucent lens 29 to acquaint himself as to the condition of the smoke then passing through the flue bridge 1. The degree of brilliancy of the light showing 115 through the translucent lens 29 is the factor or basis which determines the condition of the smoke. If the latter is very dense the light showing through the translucent lens 29 will obviously be correspondingly dim, 120 while if the smoke contains less carbon the light will be correspondingly brighter. In viewing the light through a translucent lens 29, as stated, variations in the degree of brilliancy of the light are very much more pro- 125 130

nounced than if viewed through a transparent lens.

The present invention provides a most efficient device of its kind, which will acquaint the operator of exact combustion conditions, resulting in the economical and efficient operation of the combustion apparatus equipped therewith.

What I claim is:

- 10 In combination, a smoke indicator comprising a light casing having a reduced inner end communicably joined with the flue bridge of a combustion apparatus, a vision casing, a supporting tube carrying said vision casing at the outer end thereof and having an enlarged inner end communicably joined with the flue bridge, said light casing and said vision casing being horizontally aligned relatively to each other on respective sides of the flue bridge, a light tube mounted on the top of said light casing and having its lower end opening into the latter, an illuminating element removably supported in said light tube, a top cover for said light tube having a reflecting surface on its underside, an inclined mirror reflector having its upper end disposed outwardly mounted in said light casing outwardly of said light tube, a vertically extending transparent lens mounted in said light casing and being disposed inwardly of said light tube, an inclined mirror reflector having its upper end disposed inwardly mounted in said vision casing, a vision tube depending from the bottom of said vision casing and having its upper end opening into the latter, and a horizontally extending translucent lens mounted in said vision tube, substantially as described and for the purpose set forth.
- 40 In testimony whereof I affix my signature.

HAROLD A. HORNER.
